Application May 14, 1941, Serial No. 393,366

5 Claims. (Cl. 123—169)

This invention relates to a spark plug.

The invention has for an object to provide a novel and improved construction of spark plug particularly adapted for use as a shielded spark plug for aeronautical use to enable aircraft engines to be operated with maximum efficiency.

With these general objects in view and such others as may hereinafter appear, the invention consists in the spark plug, and in the various structures, arrangements and combinations of parts hereinafter described and particularly defined in the claims at the end of this specification.

In the drawing illustrating the invention, Fig. 1 is a cross sectional view of a spark plug embodying the present invention; and Fig. 2 is a cross sectional view of a modified form of spark plug embodying the invention.

In general, the present invention aims to provide a novel construction of a spark plug of the type illustrated and described in the United States Patent to Hastings, No. 2,069,951, issued February 9, 1937, and which is particularly adapted for use as a shielded spark plug for aeronautical use. One feature of the present invention resides in the provision of a moulded insulator formed within a socket in the upper portion of the metallic shell or outer electrode and about the upper portion of the inner electrode and a portion of an inner tubular ceramic insulator whereby to form a gas tight and electrically tight bond. The upper portion of the outer metallic shell may be detachable and such upper portion together with the inner electrode and the ceramic tubing may be secured together by the moulded insulator to form a replaceable unit. The moulded insulator may and preferably will comprise an insulating composition such as a phenolic-formaldheyde resinous composition or other suitable insulating material characterized by a transformation from an initial fusible and reactive state to a final infusible one upon heating.

Another feature of the invention resides in a shielded spark plug of novel and improved construction having novel connecting means arranged to receive an adapter formed on the end of an insulated cable connector by which the distance through which the current must pass to form a short circuit between the top of the plug and the top of the inner electrode is materially lengthened without increasing the overall length of the plug.

Referring now to the drawing, 10 represents an outer metallic electrode having a longitudinally extended bore within which are positioned the

inner electrode 12 and a tubular insulating member 14 preferably of a ceramic composition. As shown in Fig. 1, the tubular insulator 14 is reduced in outside diameter at its lower end and is arranged with the inner electrode to substantially fill the bore within the outer electrode and to terminate in substantially the plane of the outer electrode to the end that during the operation of the plug, sparks are caused to traverse across the end of the insulating member. The lower end of the inner electrode or firing pin 12 is preferably reduced in diameter to receive a platinum sleeve 16 which may be silver soldered to the inner electrode, and the lower end of the outer electrode may be bored out as shown to receive a platinum sleeve 18 similarly secured thereto in order to provide efficient sparking contacts.

The outer shell or metallic electrode 10 is extended for the full length of the plug to form a protective metallic shell for shielding the plug, and as herein shown, the upper end thereof may comprise a detachable member 20 having a threaded connection with the main body portion 10 of the plug.

As illustrated in Fig. 1, the upper portion of the metallic shell 10 and the detachable portion 20 thereof are provided with an enlarged bore or socket through which the ceramic insulation and the inner electrode extend, the inner electrode being extended for the full length of the plug and substantially flush with the top of the outer shell. An asbestos gasket 22 is provided at the lower end of the enlarged bore between the outer electrode and the ceramic tube 14 in order to form a protection for the moulded insulation against hot gases of combustion passing upwardly between the ceramic tube and the metallic body of the plug.

With the parts in their assembled relation thus far described, the phenolic resin, "Micalex" or other mouldable plastic, in its fusible state is introduced into the bore or socket of the outer shell to form a body of insulation 24 within the socket and about a portion of the ceramic tube 14 and the upper portion of the inner electrode 12, to form a gas tight and electrically tight bond between the parts. A flanged and skirted member 26 preferably of metal may be provided between the upper portion 20 and the body portion 10 of the metallic shell, as shown, in order to provide a gasket against which the upper portion 20 may be tightened so as to assist in forming a gas tight seal. The skirted portion of the member 26 may be moulded in the plastic insulator 24 to form a firm bond therewith.

As shown in Fig. 1, the upper portion of the inner electrode 12 is preferably provided with grooved portions 23 in order to effect a firm bond between the plastic insulator 24 and the upper portion of the inner electrode, and in practice, such upper portion may and preferably will be provided with a thin coating of "Vinylite" resin or other equivalent thermoplastic material, as indicated by the stipple work 25, such material preferably having substantially the same fusing temperature as the plastic insulator in order to provide a more efficient bond and to form an efficient gas tight seal between the plastic insulator and the center electrode. An annular metallic member 30 is secured about the top of the center electrode 16, as shown, in order to increase the effective contact surface with the lead-in cable connector, as will be described.

As herein shown, the cable connector comprises an insulating elbow, one arm 32 of the elbow being detachably secured to the top of the spark plug and enclosing a conductor 34, and the other arm 36 enclosing a cable lead 38. The elbow is provided with a metallic outer shell 40 having a flanged portion 42 at its connecting end which is engaged by a nut 44 arranged to be screwed down over the top of the plug and the flanged portion 42, as shown. The elbow is preferably lined with a synthetic phenolic resin composition, such as "Bakelite," moulded within the elbow.

The conductor 34 is preferably pointed at its upper end and adapted to pierce the insulated lead-in wire 30 to form a firm connection therewith. As herein shown, the conductor is carried by a detachable adapter 50 which is preferably in threaded engagement with the interior of the arm 32 in order to permit the conductor 34 to be screwed into engagement with the lead-in wire. The adapter 50, as indicated, is formed from a moulded plastic insulating material, and as herein shown, is provided with an annular skirt 52 which is arranged to be received within an annular groove 54 formed in the top of the insulator 24 of the spark plug. The lower end of the conductor 34 may be provided with the usual spring connection 56 in engagement with the top of the electrode 12.

From the description thus far, it will be observed that the above described construction of the shielded spark plug is such as to reduce to a minimum the dissipation of the current through leakage paths. The manner of engagement of the adapter 50 with the top of the spark plug is such as to provide a greatly increased leakage path from the top of the inner electrode 12 and the top of the outer shell of the spark plug without increasing the length of the plug and may permit a reduction in the length of the plug to adapt it for use in limited spaces. As herein shown, the path of leakage between the top of the inner electrode 12 and the top of the outer shell is lengthened by the annular skirt 52 to require the current to pass downwardly in the groove 54 and then upwardly on the outer surface of the skirt before it can reach the top of the spark plug. As is known, the connecting member in a conventional commercial form of shielded spark plug extends down into the interior of the plug to provide a leakage path of approximately three quarters of an inch. With the present construction, this leakage path may be increased to approximately one and one-eighth inches without increasing the overall length of the spark plug. This increased leakage

path is particularly desirable in an aircraft spark plug since the resistance to such leakage is materially reduced at high altitudes. For the purpose of enhancing heat conduction, the outer walls of the plug may be ribbed, as shown, although for most purposes this feature is not necessary.

Referring now to Fig. 2, a modified form of a shielded spark plug may include an outer electrode comprising a lower metallic shell 60 and an upper shell 62 in threaded engagement therewith. The inner electrode 64 is preferably cemented within a bore provided in a main insulator 66 composed of a vitrified inorganic material such as porcelain. The main insulator 66 with the inner electrode is received within the lower shell 60 and is provided with an enlarged portion 68 arranged to rest against a shouldered portion 70 within the lower shell, as shown. A suitable gas-10 ket 72 may be provided between the shoulder 70 and the main insulator. The upper shell 62 is extended within the lower shell to form a shoulder 74 arranged to engage the upper part of the enlarged portion 68 of the main insulating tube 15 66. A second gasket 76 may be provided between these surfaces whereby to prevent the hot gases of combustion from leaking between the insulator 66 and the lower shell 60.

The main insulating tube 66 extends upwardly 20 into the upper shell 62 for a substantial distance, as shown, and a second insulating tube 78 extending from the top of the plug and downwardly beyond the top of the main insulator 66 is arranged to be inserted between the upper shell 60 25 and the main insulator 66 carrying the inner electrode 64. Thus, an insulated socket 80 is formed in the top of the plug which is arranged to receive the conventional shielded connector indicated generally by the numeral 82.

The lower end of the porcelain insulator 66 30 may be tapered as shown and filled into a correspondingly tapered socket in the outer electrode, and the ends of the outer and inner electrodes and the insulator are preferably arranged to terminate 35 in substantially the same plane so that during operation the spark is caused to travel across the end of the insulator.

While the preferred embodiments of the invention have been herein illustrated and described, it will be understood that the invention may be embodied in other forms within the scope of the following claims.

Having thus described the invention, what is claimed is:

55. 1. A shielded spark plug comprising an outer electrode including an elongated hollow metallic member, an inner electrode coextensive with the length of said outer electrode, an elongated tubular insulating member positioned between said electrodes for a major portion thereof, and a moulded insulating member within the upper portion of said hollow member and surrounding the upper portion of said inner electrode and said tubular insulating member whereby to form a substantially gas tight bond between said upper portions of the plug, said outer electrode including a detachable upper portion whereby to form a replaceable unit with said moulded insulator, tubular insulator and inner electrode.
60. 2. A shielded spark plug comprising an outer electrode including an elongated hollow metallic member, an inner electrode coextensive with the length of said outer electrode, an elongated tubular insulating member positioned between said electrodes for a major portion thereof and a
65. 3. A shielded spark plug comprising an outer electrode including an elongated hollow metallic member, an inner electrode coextensive with the length of said outer electrode, an elongated tubular insulating member positioned between said electrodes for a major portion thereof and a
70. 4. A shielded spark plug comprising an outer electrode including an elongated hollow metallic member, an inner electrode coextensive with the length of said outer electrode, an elongated tubular insulating member positioned between said electrodes for a major portion thereof and a
75. 5. A shielded spark plug comprising an outer electrode including an elongated hollow metallic member, an inner electrode coextensive with the length of said outer electrode, an elongated tubular insulating member positioned between said electrodes for a major portion thereof and a

moulded insulating member within the upper portion of said hollow member and surrounding the upper portion of said inner electrode and said tubular insulating member whereby to form a substantially gas tight bond between said upper portions of the plug, the upper portion of said inner electrode being provided with a thin coating of a thermoplastic binder having a softening temperature approximately the same as said moulded insulating member whereby to provide a gas tight seal between the latter and said inner electrode.

3. A shielded spark plug comprising an outer electrode including an elongated hollow metallic member, an inner electrode coextensive with the length of said outer electrode, an elongated tubular insulating member positioned between said electrodes for a major portion thereof, and a moulded insulating member within the upper portion of said hollow member and surrounding the upper portion of said inner electrode and said tubular insulating member and an asbestos gasket interposed between the lower end of said moulded insulator and said outer electrode and surrounding said tubular insulating member whereby to form a substantially gas tight bond between said upper portions of the plug.

4. A shielded spark plug comprising an outer electrode including an elongated hollow metallic member, an inner electrode coextensive with the length of said outer electrode, an elongated tubular insulating member positioned between said electrodes for a major portion thereof, and a moulded insulating member within the upper por-

tion of said hollow member and surrounding the upper portion of said inner electrode and said tubular insulating member whereby to form a substantially gas tight bond between said upper portions of the plug, said outer electrode including a detachable upper portion whereby to form a replaceable unit with said moulded insulator, tubular insulator and inner electrode, and a metallic gasket between said detachable portion and the body portion of said outer electrode and moulded to said moulded insulating member.

5. A shielded spark plug comprising an outer electrode including an elongated hollow metallic member, an inner electrode coextensive with the length of said outer electrode, an elongated tubular insulating member positioned between said electrodes for a major portion thereof, and a moulded insulating member within the upper portion of said hollow member and surrounding the upper portion of said inner electrode and said tubular insulating member whereby to form a substantially gas tight bond between said upper portions of the plug, the upper portion of said moulded insulator being provided with an annular groove arranged to receive a cable lead contact adapter whereby to materially increase the leakage path of the current between the upper portion of said inner electrode and the top of said outer electrode.
